(57) **CLAIM**

We claim the ornamental design for a sloped brush head, as shown and described.

DESCRIPTION

FIG. 1 is a perspective view of a sloped brush head.

FIG. 2 is a right-side elevation view thereof.

FIG. 3 is a left-side elevation view thereof.

FIG. 4 is a front elevation view thereof.

FIG. 5 is a rear elevation view thereof.

FIG. 6 is a top plan view thereof; and,

FIG. 7 is a bottom plan view thereof.

The broken lines in the drawing figures illustrate features of the sloped brush head that form no part of the claimed design.

1 Claim, 4 Drawing Sheets
